CLAIM

The ornamental design for a large brochure pocket, as shown and described.

DESCRIPTION

FIG. 1 is a perspective view of a large brochure pocket in accordance with my invention;

FIG. 2 is a front elevational view thereof;

FIG. 3 is a rear elevational view thereof;

FIG. 4 is a left side elevational view (the right side elevational view being a mirror image thereof);

FIG. 5 is a top plan view thereof; and,

FIG. 6 is a bottom plan view.

The broken line showing of the mounting strips and mounting holes is for illustrative purposes only and forms no part of the claimed design.
